UNITED STATES PATENT OFFICE.

GUSTAVE C. BEVAN, OF INDIANA HARBOR, INDIANA, ASSIGNOR OF ONE-HALF TO ROY C. CLARK, OF INDIANA HARBOR, INDIANA.

TANK-CAR VALVE.

Application filed August 21, 1920. Serial No. 405,067.

To all whom it may concern:

Be it known that I, GUSTAVE C. BEVAN, a citizen of the United States, residing at Indiana Harbor, in the county of Lake and 5 State of Indiana, have invented new and useful Improvements in Tank-Car Valves, of which the following is a specification.

This invention relates to improvements in valves for tank cars, the present invention 10 being an improvement over that described in the application filed by me on July 31, 1920, Serial No. 400,541.

The general object of the present invention is to locate the valve within the tank 15 or container, at the bottom thereof, and to provide means whereby it may be easily secured in place.

Another object of the invention is to provide means whereby the valve plug may be 20 given an initial vertical movement before being rotated to open or close the outlet port or ports, this vertical movement facilitating the rotation of the plug.

This invention also consists in certain 25 other features of construction and in the combination and arrangement of the several parts, to be hereinafter fully described, illustrated in the accompanying drawings and specifically pointed out in the appended 30 claims.

In describing my invention in detail, reference will be had to the accompanying drawings wherein like characters denote like or corresponding parts throughout the several 35 views, and in which:—

Figure 1 is a longitudinal sectional view of the invention.

Figure 2 is a similar view of a slightly different form.

40 Figure 3 is a similar view of another form.

Figure 4 is a section on line 4—4 of Figure 1.

Figure 5 is a section on line 5—5 of Figure 3.

45 Referring to Figures 1 and 4, 1 indicates a portion of the bottom part of the tank or container and 2 indicates the opening formed therein. 3 indicates the extension or outlet spout for the contents of the tank, this extension being provided with a flange 4 which is riveted to the bottom of the tank around the opening 3, as shown at 5. The upper face of said flange is provided with a recess 6 which receives a plate 7 which is also 50 riveted to the bottom 1 as shown at 8. This

plate is provided with an opening 9 which registers with the bore of the spout and said plate is also provided with an annular groove 10 which is concentric to the opening.

The improved valve comprises a casing 11 which is provided with a circular base 12 having an annular projection 13 on its bottom for engaging the groove 10, a packing ring 14 being located in the groove. Ribs 15 connect the side walls of the casing with the base and said casing is formed with the tapered bore 16 and the oppositely arranged ports 17. The valve plug 18 is of tapered formation to conform to the shape of the bore of the casing and the lower part of 70 this plug is provided with a pair of outlet passages 19. The upper part of the plug is reduced to receive the cup member 20 and the upper end of the reduced portion is screw threaded to receive the nut 21. The bottom of the nut is adapted to enter the cup-shaped member and a coil spring 22 is placed in said member with its upper end engaging the nut. The cup-shaped member is provided 75 with a flange for extending over the top of the casing and ball bearings 23 are placed between said member and the top of the casing. A coil spring 24 is located below the bottom of the plug and said spring rests upon the lugs 25 which are formed on the 80 interior walls of the extension or spout at the upper end of its bore. This spring and spring 18 serve to hold the plug in firm engagement with the walls of the casing and the tension of these springs can be adjusted 85 by means of the nut 21.

The upper end of the reduced part of the plug is provided with a square socket 26 which is adapted to receive the square end of the valve operating rod 27, the parts being 90 held together by a pin 28 which also passes through the nut 21 and acts to hold said nut in adjusted position.

At the junction of the extension 3 with its flange inner and outer grooves 29 are formed 100 for weakening this part of the extension so that if the extension should come in contact with an obstruction along the track or be struck in any other way the extension would break off at this weakened point and thus 105 remove the danger of the other parts being pulled away from the bottom of the tank and spilling the contents.

It will be seen that the plug can be rotated 110 to bring the passages therein into register

- with the ports 17 in the valve casing so as to permit the contents of the tank to flow into the extension or spout. Then by giving the plug a quarter turn these passages will be moved out of register with the ports so as to cut off the flow. By depressing the rod 27 before rotating it the plug will be lowered slightly so as to free it from the walls of the bore, thus permitting it to be rotated easily.
- 10 The springs will return it to its seat as soon as the pressure is removed from the rod. The ball bearings permit the cup-shaped member to move freely upon the casing with the plug.
- 15 The connection of the extension and plate 7 with the tank and the valve casing is a tight one to prevent the escape of oil and this arrangement also permits the valve to be readily positioned within the tank.
- 20 In the modification shown in Figure 2 the plate 7 is omitted as is also the recess in the flange of the extension and the base 12' of the valve is bolted directly to said flange. This flange is also provided with the groove 25 for receiving the packing ring and the projection on the valve base. In other respects this form of the invention is similar to that before described.

The form of the invention shown in Figure 3 is similar to that shown in Figure 2 but this figure shows the extension 3' as being provided with the steam ports 3" for delivering the steam introduced at the inlets 3" against the flange of the extension whereby the parts carrying the valve are heated to make the contents of the tank run freely therefrom in cold weather.

The lower end of the extension is screw threaded to receive the usual closing plug 40 which may be attached to the extension by a flexible connection which has a part passing through the eye 3^a on the extension.

It is thought from the foregoing description that the advantages and novel features 45 of my invention will be readily apparent.

I desire it to be understood that I may make changes in the construction and in the combination and arrangement of the several parts, provided that such changes fall within the scope of the appended claims. 50

What I claim is:—

1. A valve for tanks comprising in combination with an outlet spout, of a casing provided with a tapered bore gradually increasing in diameter towards the bottom of the bore, said casing provided with a pair of diametrically opposed openings in its sides, a valve plug rotatable in said bore and provided with pasageways adapted to communicate with said openings and said outlet spout, a plurality of circumferentially spaced radial lugs formed on said outlet spout, and a spring supported by said lugs and engaging said valve plug.

2. A valve comprising in combination with an outlet spout, a casing having a bore and openings, a valve plug rotatable in said bore and adapted to establish communication between said openings and the outlet spout and a spring acting against said plug and supported at spaced points by said spout.

3. A valve comprising in combination with an outlet spout, a casing provided with a tapering bore, a valve plug rotatable in said bore, a reduced upper end formed on said plug, a cup shaped member rotatable relative to the plug and the casing, a spring within said cup shaped member and engaging the cup shaped member, a nut on said reduced end for clamping engagement against said spring to yieldably connect the plug and cup shaped member for unitary rotary movement, a plurality of circumferentially spaced radial lugs carried by said outlet spout, and a spring supported on said lugs and engaging said plug.

In testimony whereof I affix my signature.

GUSTAVE C. BEVAN.
